UNITED STATES PATENT OFFICE.

ULRICH BAUMANN, JR., OF WOODCLIFF, NEW JERSEY.

APPARATUS FOR DRYING TEXTILE FABRICS.

Application filed March 24, 1926. Serial No. 96,966.

This invention relates to improvements in the treatment of textile fabrics, and has particular reference to an apparatus for drying fabrics. In my co-pending application, 5 Serial No. 50,175, filed August 14, 1925, allowed February 6, 1926, there is described a machine wherein fabrics wound upon drums are passed through a plurality of baths to effect the dyeing of the fabrics. After the 10 dyeing process has been completed, it has been customary to convey the drums with the fabrics thereon to a drying room where the fabrics, while on the drums, are subjected to the action of heated air. This air 15 penetrates the fabric from both the exterior of the roll and from the interior thereof, the drum being of an openwork construction. It has been found that the intermediate layers or convolutions of the roll of fabric do 20 not become thoroughly dried unless the fabric is allowed to remain in the drying room for twelve hours or more.

An object of the present invention is to greatly facilitate the drying of fabric on a 25 drum by passing heated air from the interior of the drum outwardly through the fabric thereon.

Another object is to close the open ends of a drum by means of closure elements into 30 which heated air is injected under pressure, so that said air will pass through the drum and the fabric thereon and thereby quickly and thoroughly dry said fabric.

The above and other objects will appear 35 more clearly from the following detail description, when taken in connection with the accompanying drawing, which illustrates preferred embodiments of the inventive idea.

In the drawing—

40 Figure 1 is an elevation, partly in section, of one form of apparatus for carrying out the invention;

Figure 2 is a section on the line 2—2 of Figure 1; and

45 Figure 3 is a view similar to Figure 1 showing a slightly different form of apparatus.

Referring more particularly to Figures 1 and 2, the apparatus for carrying out the 50 invention is shown as consisting of a pair of standards 4 each having a laterally extending support or bearing 5 at its upper end provided with a recess 6 in its extremity for receiving one of the trunnions 7 of a drum 55 8 upon which the fabric 9 is wound. After

the drum and fabric have been passed through the dyeing machine described in the above mentioned application, said drum is mounted between the standards 4 in the manner above described preparatory to drying the fabric. The drums employed with said dyeing machine are of openwork construction and consist of annular end members 10 having spaced radial braces 11 from the inner ends of which extend the trunnions 60 7. The end members are connected by spaced strips 12 which combine to form the wall of the drum and about which the fabric 9 is wound. By thus providing an openwork construction of drum, it will be apparent 65 that heated air may pass into the ends of the drum and from thence outwardly between the strips 12, as indicated by the arrows in Figure 1.

Each of the bearings 5 has secured thereto 75 at 13 an end closure 14 which, in the present embodiment, is made of a flexible material, such as rubberized fabric or the like, and through which the heated air cannot pass. By making this end closure or hood of flexible 80 material the same may be easily fitted over the adjacent end of the roll of fabric 9 mounted on said drum. A binding element 15, such as a cord, may then be tied about the portion of the closure 14 which overlaps 85 the end of the fabric roll so as to secure the closure in position and prevent the escape of heated air between the same and the outer surface of said roll. One of the closures 14 is provided with an extension 16 forming an 90 inlet to which a hose or other suitable connection 17 is attached for the purpose of injecting heated air into the compartment formed by the closure 14. The hose 17 may be connected to any suitable source of heated 95 air capable of injecting said air into the closure 14 under pressure. The air entering the closure 14 at the right of Figure 1 will pass through the adjacent end of the drum and some of said air will enter and fill the 100 compartment formed by the closure 14 at the left of said figure. The air being under pressure will be forced outwardly between the strips 12 of the drum and from thence will pass through the various layers or convolutions of the fabric roll to quickly and thoroughly dry the same. It has been found in actual practice that a roll of fabric forty feet in length can be thoroughly dried in approximately one hour. After the fabric is 110

dried the binding elements 15 are removed to permit of the detachment of the end closures 14 from the fabric, after which the drum may be lifted from its supports and 5 the fabric 9 unwound therefrom.

In Figure 3, the closure 18 is made of metal and of cylindrical form so as to permit of the same being tightly fitted over the adjacent end of the roll of fabric 9. The closure is 10 also provided with an inlet 19 to which the hose 20 may be connected for the purpose of injecting heated air under pressure into the adjacent end of the drum 8. Thus the heated air will be caused to pass into the interior of the drum and outwardly through 15 the fabric wound thereon, thereby thoroughly drying the same, as described in connection with the form of apparatus shown in Figure 1.

20 What is claimed is:

1. The combination with a drum having open ends and through the wall of which heated air is capable of passing; of end closures for said drum forming compartments having communication with the interior of said drum, and means for injecting heated air into said compartments so, that said air will pass into the interior of said drum and from thence outwardly through a 25 fabric wound upon the wall of said drum.
2. The combination with a drum having open ends and through the wall of which heated air is capable of passing; of end closures for said drum having communication with the interior thereof, and means for injecting heated air under pressure into 30 one of said closures so, that said air will pass into the interior of said drum through the ends thereof and from thence outwardly

through a fabric wound upon the wall of the 40 drum.

3. The combination with a drum having open ends and through the wall of which heated air is capable of passing; of end closures for said drum having portions thereof overlapping adjacent ends of a roll of fabric wound upon the wall of the drum, and means for injecting heated air into said end closures so that said air will pass through the open ends of the drum into the interior thereof and from thence outwardly through 45 the fabric wound upon the drum.

4. The combination with a drum having open ends and through the wall of which heated air is capable of passing; of end closures for said drum having portions thereof overlapping adjacent ends of a roll of fabric wound upon the wall of the drum, and means for injecting heated air into one 50 of said end closures so that said air will pass therefrom into the interior of the drum and from thence outwardly to the fabric wound upon the drum.

5. The combination with a drum having open ends and through the wall of which heated air is capable of passing; of flexible end closures for the ends of the drum having portions overlapping a roll of fabric wound upon the wall of the drum, means for securing 55 said portions to said roll, and means for injecting heated air into one of said closures so that said air will pass into the interior of the drum and from thence outwardly through the fabric wound upon the drum.

In testimony whereof I have affixed my 60 signature.

ULRICH BAUMANN, JR.
